REFRIGERATION

George A. Brace, Takoma Park, D. C., assignor to
The Hoover Company, North Canton, Ohio, a
corporation of Ohio

Application March 20, 1942, Serial No. 435,491

12 Claims. (Cl. 62—118)

This invention relates to refrigeration and more particularly to an improvement in intermittent absorption refrigerating machines of the type which use a solid absorbent, such as strontium chloride, and a refrigerant such as ammonia. In this type of absorption machine the absorber-generator is alternately heated to drive the refrigerant from the absorbent and cooled to reabsorb the refrigerant in the absorbent. The condenser is usually spaced to one side or above the absorber-generator and the parts of the apparatus are otherwise suitably arranged for assembly with a domestic refrigerator cabinet.

In such an apparatus during the heating period the vapor driven from the absorbent in the absorber-generator passes through a conduit leading to the condenser. Some of these vapors are inevitably condensed in this conduit and flow back to the absorber-generator in liquid form. The above is especially true in air cooled machines to which this invention relates. At the start of the absorption period in such machines, sudden cooling of the absorber-generator causes a rapid decrease of the internal pressure at this point, with the result that liquid refrigerant in the condenser is carried back into the absorber-generator.

It has been found that the absorbing ability of the absorbent material is greatly impaired, if not in fact destroyed, wherever contacted by liquid refrigerant. Accordingly, it is of paramount importance to take effective measures for safeguarding the absorbent against contact by the liquid at any time. Certain attempts to deal with the foregoing problem have been proposed but have proven inadequate, untrustworthy and of limited value.

It is accordingly an object of the present invention to provide an intermittent absorption refrigerator so designed and constructed that it is impossible for liquid refrigerant to return to the absorber-generator at any time and under any condition or position of the refrigerator whether in an operative or inoperative condition. More specifically, it is an object to provide means in the vapor conduit leading from the absorber-generator designed to collect and trap liquid refrigerant flowing toward the absorber-generator until such time as it can be vaporized.

Another object is to collect liquid refrigerant condensing in the vapor conduit leading from the absorber-generator during the heating period thereof, and utilizing waste heat to vaporize the same whereby to increase the efficiency of the

apparatus while preventing damage to the absorbent by the liquid.

Another object is to trap liquid refrigerant flowing toward the absorber-generator from the condenser at the beginning of a cooling period.

Still another object is to so construct a liquid trap that liquid cannot flow to the absorber-generator regardless of the position of the apparatus during shipment or other handling.

10 A further object of the invention is to provide a novel and more efficient method of producing refrigeration.

Other objects and advantages of this invention will become apparent as the description proceeds when taken in connection with the accompanying drawings in which:

Figure 1 is a diagrammatic representation of an intermittent absorption machine with this invention applied thereto;

20 Figure 2 is a vertical sectional view of the absorber-generator according to this invention; and

Figure 3 is a cross sectional view of the absorber generator of Figure 2 taken on line 3—3 of Figure 2.

25 Referring to Figure 1 of the drawings, A represents the absorber-generator, C the primary condenser, and E the evaporator. The absorber-generator A is connected by conduit 10 to the upper end of condenser C. The condenser C has a downwardly inclined slope throughout and is connected by conduit 12 to the receiving vessel 14 which forms a part of the evaporator E.

The absorber-generator A as shown in Figures 2 and 3 comprises an outer cylindrical wall 16, 35 an intermediate cylindrical wall 18, and an inner cylindrical wall 20. The inner cylindrical wall 20 has indented portions 21 which contact with the intermediate cylindrical wall 18 for a purpose to be described hereinafter. The outer cylindrical wall 16 and the intermediate cylindrical wall 18 are connected at the ends by end walls 22 welded thereto to form an absorbent medium chamber which is divided into a plurality of small chambers by plates 24 secured in good heat conducting relationship to the intermediate wall 18. Each of the plates 24 has a plurality of openings 26 therein.

As shown in Figure 2, tube 20 forming the heating chamber extends above both the cooling and the absorbent chambers for some distance. Secured to the extended portion of this tube is a chamber 28 of sufficient size to hold the maximum quantity of liquid refrigerant which would ever be present in vapor conduit 10 during any normal or abnormal condition of the apparatus.

A conduit 28 extends from the absorbent chamber to a point adjacent the uppermost portion of chamber 28 and provides a passage for the free flow of refrigerant vapor to or from the absorber-generator. As will be obvious from Figure 2, the relationship of chamber 28 and conduit 28 is such that any liquid flowing downwardly through vapor conduit 10 collects in chamber 28 and is trapped therein. If the upper end of conduit 28 terminates adjacent the heating chamber wall 20, and if the left hand side of chamber 28 is made larger than presently shown in Figure 2, as is preferable, it is impossible for liquid to return to the absorbent chamber regardless of the position in which the apparatus may be placed during shipment or other handling.

The intermediate wall 18 extends above the outer annular wall 16 and is bent inwardly at 30 and welded to the inner cylindrical wall 20. The inner cylindrical wall 20 is bent outwardly at 31 and is welded to the interior of the intermediate wall 18. The space between the inner wall 20 and the intermediate wall 18 forms a cooling chamber or heat exchange device of an indirect cooling circuit for the absorber-generator A. The entire absorber-generator, including the liquid trap, is suitably enclosed in heat insulating material to reduce heat losses to a minimum.

The inner annular wall 20 may form a combustion flue for the absorber-generator A when a liquid or gaseous fuel burner is used or, as shown in Figure 1, may form the housing for a suitable electric heating element 32. The struck out portions 21 of the inner cylindrical wall which contact with the intermediate cylindrical wall 18 form a good thermal path for transferring heat from the heating element 32 to the solid absorbent in the annular chamber between the outer cylindrical wall 16 and the intermediate cylindrical wall 18 during the heating period, and for cooling the absorber-generator uniformly throughout its height during the cooling period. This later function is facilitated by indentations 21 which divide the annular cooling chamber into vapor lift pumps by means of which the cooling liquid is continually circulated to the upper part of the chamber by rising bubbles of vaporizing cooling liquid.

The upper end of the annular space between the walls 18 and 20 is connected by conduit 34 to the upper end of the secondary condenser 36. The secondary condenser 36 has a continuous downward slope throughout and leads to a reservoir 38. The reservoir 38 is connected by conduit 40 to a valve chamber 42. The valve chamber 42 is connected by conduit 44 to the lower end of the space between the annular walls 18 and 20. The valve 46 is designed to be operated by a snap acting device 48 of any suitable construction.

The conduits 50 of the evaporator E extend downwardly from the bottom of the receiving chamber 14 and are in direct thermal contact with the ice freezing chamber 51. From the lower ends of the conduits 50 extend conduits 52 which are bent backwardly and forwardly in the form of a sinuous coil having a continuous upward slope and enter the receiving chamber 14 above the point of connection of the conduits 50.

A thermostatic bulb 56 contacts the outer surface of the absorber-generator A and is connected by a capillary tube 58 to a bellows 60 which upon expansion and contraction is adapted to operate the snap acting device 48. The bulb 56, tube 58 and bellows 60 are filled with a suit-

able thermally responsive fluid so that the bellows 60 will expand and contract upon variations in temperature of the bulb 56 as is well known in the art. A snap acting switch 62 of any suitable construction is positioned to be actuated by the snap acting device 48.

A thermostatic bulb 64 in thermal contact with the freezing chamber 51 is connected by a capillary tube 66 to a bellows 68. The bulb 64, tube 66 and bellows 68 are filled with a suitable vaporizable fluid so that the bellows 68 will expand and contract upon variations in temperature of the ice freezing chamber 51 as is well known in the art. Upon expansion and contraction the bellows 68 is adapted to actuate a snap acting device 70 which in turn operates the valve 72 in the conduit 40 and an electric switch 74.

One side of the power line is connected to one side of the switch 74. The other side of the switch 74 is connected by a suitable conductor, as shown, to one of the contacts of switch 62. The other contact of switch 62 is connected by a suitable conductor to one side of the heating element 32, the other side of which is connected to the other side of the power line.

The absorber-generator A is charged with a suitable solid absorbent such as strontium chloride and a refrigerant such as ammonia, while the indirect cooling system is charged with a vaporizable medium such as methyl chloride, all as is well known in the art. When strontium chloride absorbs ammonia, addition compounds, such as $\text{SrCl}_2 \cdot 1\text{NH}_3$, $\text{SrCl}_2 \cdot 2\text{NH}_3$, $\text{SrCl}_2 \cdot 4\text{NH}_3$ and $\text{SrCl}_2 \cdot 8\text{NH}_3$ are formed. As the addition compounds are formed, strontium chloride expands and when 8 molecules of ammonia have been absorbed for every molecule of strontium chloride, it will occupy a volume of approximately $2\frac{1}{2}$ times its original volume.

Preferably sufficient strontium chloride is charged into the absorber-generator, that the walls thereof will remain under pressure due to the expanded strontium chloride even at the end of the generating period of the absorber-generator. When the absorber-generator is fully charged with ammonia, its walls will of course be under a greater pressure due to the expanded absorbent.

The indirect cooling circuit for the absorber-generator A is suitably charged with a vaporizable liquid such as methyl chloride. The pressure within the indirect cooling circuit when using methyl chloride is relatively low; hence, the snap acting device 48 may be led into the interior of the valve chamber 42 through a suitable flexible joint 76.

As shown in Figure 1, the bellows 68 is in an expanded position with the result that the valve 72 is open and the switch 74 is closed. The switch 62 is set so that electricity will be conducted to the heating element 32 of the absorber-generator A which will be heated. The bellows 60 is contracted with the result that the snap acting device 48 will be positioned to the left and the valve 46 will be closed.

With the control set as in Figure 1 the heating of the absorber-generator A by the heating element will drive refrigerant vapor from the solid absorbent contained therein. This refrigerant vapor will pass by the conduit 28, chamber 28 and conduit 10 to the condenser C where it will condense and the heat of condensation will be carried away by air flowing over the heat rejecting fins mounted on the tubes in the

condenser. Upon condensing the liquid refrigerant will flow downwardly through the tubes of the condenser C into the receiving vessel 14 and fill the tubes 50 and 52 of the evaporator E.

During the generation of refrigerant in the absorber-generator A some of the refrigerant vapor may condense in the conduit 10 and flow backwardly toward the absorber-generator A. This is particularly true at the beginning of the heating period at which time conduit 10 is cold and consequently serves as a fairly efficient condenser. However, by reason of the construction hereinabove described, liquid condensed in conduit cannot reach the absorber-generator, but instead becomes trapped in chamber 28. After a short period of operation, trap 28 will become heated by waste heat not absorbed by the absorber-generator proper. As a result, the liquid will vaporize and pass to the condenser and the evaporator where it is available to produce refrigeration at a later time. Thus, the liquid is automatically removed from the trap as it collects without expense and by the use of waste heat.

During the heating of the generator-absorber A the small amount of auxiliary cooling fluid which may remain in the space between the cylinders 18 and 20 of the generator-absorber A will quickly vaporize and flow by conduit 34 into the secondary condenser 36. The air flowing over the fins in the condenser 36 will carry away the heat of condensation of the auxiliary fluid whereby it will condense and flow downwardly through the tubes of the condenser 36 into the reservoir 38. This liquid auxiliary cooling fluid cannot return to the absorber-generator A at this time because the valve 45 is closed.

As soon as the refrigerant has been liberated from the absorbent in the absorber-generator A, the temperature of the absorber-generator A will rise abruptly even though the heat applied to the absorber-generator A remains constant. This comes about by reason of the fact that so long as refrigerant is being driven from the solid absorbent the heat supplied thereto is utilized to vaporize the refrigerant, but after the refrigerant is vaporized, the heat supplied quickly raises the temperatures of the absorber-generator to a much higher value.

This raised temperature will cause the liquid in the bulb 56 to operate bellows 60, and push the snap acting device 48 to the right. As the snap acting device 48 moves to the right, it will operate switch 62 to de-energize the heating element 32 and to open the valve 46.

The indirect cooling system is charged with sufficient auxiliary cooling medium, so that the reservoir 38 will always contain cooling medium in liquid form. When the control operates to open the valve 46, the liquid in the reservoir 38 will be dumped into the space between the walls 18 and 20 of the absorber-generator A. Since the absorber-generator A is hot at this time the auxiliary cooling fluid will be quickly vaporized and the absorber-generator A will be quickly cooled.

The cooling of the absorber-generator A will reduce the vapor pressure therein and the solid absorbent will begin to absorb refrigerant vapor and vaporization of the liquid refrigerant in the evaporator E will begin. The vapor so formed will return to the absorber-generator A through conduit 12, condenser C, conduit 10, chamber 28 and conduit 29.

At the end of the generating period, some 75 ber 51 goes to a desired low value, which may be

liquid refrigerant is likely to be present in condenser C, and possibly in conduit 10. Since, immediately upon the termination of the generating period, cooling liquid is admitted to the cooling compartment of the absorber-generator, both the temperature and the internal pressure of the absorber-generator decreases abruptly. As a consequence, there is a flow of vapor through the condenser in the direction of the absorber-generator of sufficient magnitude to carry the liquid refrigerant with it. However, trap 28 separates the liquid from the vapor and retains it while permitting the vapor to continue to the absorber-generator where it is absorbed.

15 Due to the much lower internal pressure existing during the cooling period, liquid collecting in the trap readily vaporizes and mingles with the main stream of returning vapor.

As absorption proceeds in the absorber-generator A, the heat of absorption is transferred to the auxiliary cooling fluid in the space between the walls 18 and 20. This vaporizes the auxiliary liquid and this vapor flows to the secondary condenser 36 by conduit 34. The vapor is condensed

20 and the heat of condensation is carried away by air flowing over the heat rejecting fins on the condenser 36. The tubes of the condenser 36 have a continuous downward slope and the liquid auxiliary cooling fluid returns to the reservoir 38 to 25 be returned in due time to the space between the walls 18 and 20 for further cooling action.

When all of the refrigerant in the evaporator E is evaporated, absorption will cease in the absorber-generator A with the result that no more heat 30 will be generated therein and its temperature will be lowered to substantially room temperature by the circulating cooling medium. This will cause the fluid in the bulb 56 to contract sufficiently to collapse the bellows 60 and to shift the snap acting device 48 to the left. In this regard it is to be noted that the bellows 60 and snap acting device 48 are set so that the snap acting device will be moved to the left at the highest room temperature liable to be encountered so as to assure that the 35 unit will always be returned to the generating period under any operating conditions.

The valve in the chamber 42 will be closed so that the cooling medium cannot flow to the absorber-generator A through the conduit 44, and 40 the switch 62 will be closed so as to energize the heating element 32. The fluid in the cooling pocket of the absorber-generator A will be quickly vaporized therein by the heat supplied by the heating element 32, and the vapor will pass to 45 the condenser 36 where it will be liquefied and flow to the receiver 38 for subsequent use in producing refrigeration.

The absorber-generator A will thus automatically operate alternately on an absorption and 50 a generating period as the temperature thereof rises and falls without the necessity of providing any additional control. In the particular application of the invention herein disclosed by way of illustration, the bulb 56, bellows 60, switch 74 and valve 72 are so designed and adjusted that the temperature of the evaporator E will not fall to a value below that desired in a domestic refrigerator. It will of course be understood that in other applications of the invention, thermostat 54, 58, valve 72, switch 74 could be omitted. In this event the apparatus would operate automatically under the control of thermostat 56, 60, as will be readily apparent.

When the temperature of the freezing chamber 51 goes to a desired low value, which may be

appreciably below the average temperature of the food storage space of a domestic refrigerator, the bulb 84 will operate to collapse the bellows 88 and operate to close the valve 72 and open the switch 74. This will operate to de-energize the heating element 32 if the system is on the heating period and to close the valve 72 to stop the flow of cooling fluid if the absorber-generator is on the absorption period.

If the absorber-generator A is on the absorption period, the liquid cooling medium in the space between the walls 18 and 20 will soon vaporize due to the heat of absorption and will pass through the secondary condenser 38 where it will be condensed. Since the tubes of the secondary condenser 38 slope towards the reservoir 38, this condensed liquid cannot return to the cooling space of the absorber-generator A but will flow to the reservoir 38 and be trapped out of circuit by the closed valve 72. When the absorption of refrigerant vapor in the absorber-generator ceases, no more liquid refrigerant will evaporate in the evaporator. Thereafter the temperature of the air in the storage space will slowly rise until the control bellows 88 again acts to open the valve 72 and to close the switch 74. The unit will then continue to operate alternately on the absorption and generating periods as previously described.

While the invention has been shown and described as applied to an intermittent absorption machine having a single absorber-generator, it is to be understood that it is equally applicable to one having two absorber generators operating alternately and two evaporators operating alternately to provide continuous refrigeration.

From the foregoing it can be seen that this invention provides a novel intermittent absorption refrigerating machine in which the absorbent is protected against contact by liquid refrigerant at all times and under all conditions and on all positions of the machine.

Any refrigerant which may collect in the conduit leading from the absorber generator to the condenser during the generating period will be trapped in the vessel 28 where it is vaporized by waste heat. Any liquid refrigerant which may be carried toward the absorber-generator by returning refrigerant vapor at the start of the absorption period will likewise be trapped in the vessel 28 and vaporized.

While I have shown but a single embodiment of my invention, it is to be understood that this embodiment is to be taken as illustrative only and not in a limiting sense. I do not wish to be limited to the particular arrangement shown and described but to include all equivalent variations thereof except as limited by the scope of the claims.

I claim:

1. An intermittent absorption refrigerating machine including an absorber-generator having an absorbent receiving chamber charged with a refrigerant and an absorbent the absorbing characteristics of which are subject to impairment if the same is contacted by liquid refrigerant, a condenser above said absorber-generator, a conduit leading from said absorber-generator to said condenser, a heating tube for said absorber-generator, and a liquid trap in said conduit above said absorber-generator in direct heat exchange relationship with said heating tube and connected to said absorbent receiving chamber by an upwardly extending vapor conduit.

2. An intermittent absorption refrigerating machine including an absorber-generator, a con-

denser, a conduit leading from said absorber-generator to said condenser, a heating tube for said absorber-generator, an indirect cooling circuit for said absorber-generator having a heat exchange chamber surrounding said heating tube and a liquid trap in said conduit in heat exchange relationship with said heating tube above said heat exchange chamber.

3. An absorber-generator for an intermittent absorption refrigerator comprising, means providing a heating chamber, a heat exchange chamber surrounding said heating chamber, means for connecting said heat exchange chamber to a source of cooling fluid, an absorbent receiving chamber surrounding said heat exchange chamber, and a liquid trap communicating with said absorbent receiving chamber constructed to prevent liquid which may collect therein from flowing to the absorber-generator, said trap surrounding said heating chamber and being in direct heat exchange relationship therewith.

4. An absorber-generator for an intermittent absorption refrigerator comprising a cylindrical heating chamber, means cooperating with said chamber to form a cylindrical heat exchange chamber surrounding said heating chamber, means for connecting said heat exchange chamber to a source of cooling fluid, and means forming an absorbent receiving chamber surrounding said heat exchange chamber, said heating chamber having a plurality of spaced apart indentations therein extending into said heat exchange chamber and forming with the inner wall of said absorbent receiving chamber a plurality of fluid passages at an angle to the horizontal.

5. An intermittent absorption refrigeration machine including an absorber-generator, a condenser, a conduit leading from said absorber-generator to said condenser, a heating chamber for said absorber-generator, an indirect cooling circuit for said absorber-generator including a heat exchange chamber surrounding said heating chamber, an absorbent receiving chamber surrounding said heat exchange chamber and a liquid storage chamber in said conduit above said heat exchange chamber in heat exchange relationship with said heating tube.

6. An intermittent absorption refrigerating machine as described in the preceding claim characterized in that said heating chamber has indentations therein extending into said heat exchange chamber and cooperating therewith to provide narrow elongated fluid passages.

7. An absorber-generator for an intermittent absorption refrigerating machine comprising a cylindrical heating tube, an annular heat exchange chamber surrounding said heating tube, means for connecting said heat exchange chamber to a source of cooling fluid, an annular absorption receiving chamber surrounding said heat exchange chamber, an annular liquid trap above said heat exchange chamber surrounding said heating tube and in direct heat exchange relationship therewith and a vapor duct connected to said absorbent receiving chamber and said liquid trap.

8. An absorber-generator for an intermittent absorption refrigerating machine comprising a cylindrical heating tube, an annular heat exchange chamber surrounding said heating tube, means for connecting said heat exchange chamber to a source of cooling fluid, an annular absorbent receiving chamber surrounding said heat exchange chamber, an annular liquid trap above said heat exchange chamber surrounding said

heating tube and in direct heat exchange relationship therewith and a vapor duct connecting said absorbent receiving chamber and said liquid trap, said heating tube having indentations therein extending into said annular heat exchange chamber into heat exchange relationship with the inner wall of said absorbent receiving chamber.

9. An intermittent absorption refrigerating machine including an absorber-generator having an absorbent receiving chamber charged with a refrigerant and an absorbent, the absorbing characteristics of which are subject to impairment if the same is contacted by liquid refrigerant, a condenser, a heating tube for said absorber-generator, and a liquid trap in said conduit in direct heat exchange relationship with said heating tube and connected to said absorbent-receiving chamber by a vapor conduit, said trap being so constructed and arranged as to hold all of the liquid refrigerant with which the machine is charged regardless of the position in which the machine is placed.

10. An absorber-generator for an intermittent absorption refrigerating machine comprising a cylindrical heating tube, an annular heat exchange chamber surrounding said heating tube, an annular absorption receiving chamber surrounding said heat exchange chamber, an annular liquid trap above said heat exchange chamber surrounding said heating tube and in direct heat exchange relationship therewith and a vapor duct connecting said absorbent-receiving chamber and said liquid trap, said trap being so con-

structed and arranged as to hold all of the liquid refrigerant with which the machine is charged regardless of the position in which it may be placed.

11. An absorber-generator for an intermittent absorption refrigerating machine comprising a cylindrical heating tube, an annular heat exchange chamber surrounding said heating tube and connected to a cooling circuit, an annular absorbent-receiving chamber surrounding said heat exchange chamber, an annular liquid trap above said heat exchange chamber surrounding said heating tube and in direct heat exchange relationship therewith and a vapor duct connecting said absorbent-receiving chamber and said liquid trap, and said absorber-generator, trap and connecting vapor duct being imbedded in insulation.

12. An intermittent absorption refrigerating machine including an absorber-generator having an absorbent-receiving chamber charged with a refrigerant and an absorbent, the absorbing characteristics of which are subject to impairment if the same is contacted by liquid refrigerant, a condenser, a conduit leading from said absorber-generator to said condenser, a heating tube for said absorber-generator and a liquid trap in said conduit in direct heat exchange relationship with said heating tube and connected to said absorbent-receiving chamber by an upwardly extending vapor conduit, said absorber-generator, liquid trap and connecting vapor conduit being imbedded in insulation.

GEO. A. BRACE.
